UNITED STATES PATENT OFFICE.

FRANK BOURNE, OF MOUNT VERNON, NEW YORK, ASSIGNOR TO McELROY-GRUNOW ELECTRIC RAILWAY SYSTEM, OF BRIDGEPORT, CONNECTICUT, A CORPORATION OF NEW JERSEY.

ART OF CONTROLLING ELECTRICAL SWITCHES OPERATED BY ELECTROMAGNETS.

SPECIFICATION forming part of Letters Patent No. 706,011, dated August 5, 1902.

Application filed November 8, 1901. Serial No. 81,588. (No model.)

To all whom it may concern:

Be it known that I, FRANK BOURNE, a citizen of the United States, residing at Mount Vernon, county of Westchester, and State of New York, have made a new and useful Invention in the Art of Controlling Electrical Switches Operated by Electromagnets, of which the following is a specification.

My invention has for its objects, first, to provide a novel method of operation of such devices, whereby the circuit which the switch controls will surely be opened when the controlling-circuit is broken; second, to provide a novel method of controlling the operation of such devices, whereby on closing the circuit to the controlling-magnet two independent forces will be set up which act jointly and tend strongly to close the working circuit, one of said forces acting ultimately to oppose the action of the other in such manner that when the controlling-circuit is interrupted this tendency to oppose will cause the switch to surely effect the interruption of the working circuit. These objects are accomplished in the use of the devices hereinafter described, for a full and clear understanding of the operation of which reference is had to the accompanying drawings and the following specification, the novel method of operation of said apparatus being claimed at the end of the specification.

The drawings, embracing Figures 1 and 2, are sectional views of modified forms of apparatus designed to practice the methods hereinafter claimed, parts of the structures being shown in elevational view.

Referring first to Fig. 1, B represents an insulating base or board, to which are secured two downwardly-depending metallic arms F, slotted at their lower ends, as shown at S S, S S. C represents the exterior and D the interior concentric poles of a magnet of the bell type, between which poles is located the energizing-coil M, connected at its opposite ends to binding-posts B' B², w w being a conductor connecting the same with a source of current-supply (not shown) and any preferred means for opening and closing the circuit thereto. A represents the armature of the magnet, having an upwardly-extending pole

of substantially the same proportions as the pole D, the disk portion of this armature being of substantially the same diameter as the exterior pole C. G G' represent non-magnetic supports, preferably wood, and E a solenoid-core, preferably slotted, as shown, and adapted to receive adjustably the shouldered ends of said supports. This solenoid-core may be varied in length and thickness or solid, if preferred, the essential feature being that when the circuit is closed the major portion of the core shall be located above the median line x x of the magnet, so as to exert a counter-acting force against that of the armature proper. I is a metallic band tightly secured around the upper end of the insulating-support G and provided with a binding-post J, to which is secured a branch conductor W, running to a working source of current-supply. (Not shown.) H is a movable terminal or yielding contact-spring, made, preferably, of laminated plates of copper and so arranged that when the circuit is closed the upper or free ends thereof make good contact with a fixed terminal, preferably a disk-like copper plate P, secured directly to the under face of the insulating-base B. This copper plate P is in turn connected to a binding-post E³ and to a branch conductor W', running to the point where the working current is to be used. The armature A is attached directly to the support G' in any preferred manner, and the support G is adapted to move vertically through an opening in the base B. In the construction of the apparatus the supports G and G' are inserted within the opposite ends of the slotted solenoid-core E, preferably to such points that when the switch is closed and the contact-springs H resting firmly against the under face of the plate P the major portion of the solenoid-core will be located above the median line x x of the switch-operating magnet and the armature out of contact with the pole C, as clearly shown in both figures of the drawings.

Fig. 2 of the drawings illustrates a modified form of the invention, which differs from that shown in Fig. 1 only in that instead of providing a disk armature A, I substitute therefor a bell-armature having concentric

poles C' D', which are substantially similar in all respects to the corresponding parts C D.

In both figures of the drawings the concentric poles C D are adjustably suspended from the base B by arms F, slots S S being provided for screws s s s s, the arrangement being such that the entire switch-operating magnet may be adjusted as desired for the purpose of effecting the best results.

10 In the operation of both forms of the apparatus the circuit is closed first through the conductor *w w*. At this stage of the proceeding the armature and the solenoid-core E, together with their attached parts constituting 15 the movable part of the switch, are in the lowest position, so that the contact-springs H are widely separated from the contact-plate P. Consequently there is a double magnetic effect upon the movable part—that 20 is to say, two magnetic forces are acting, one due to the action of the poles C D and armature A, Fig. 1, or its equivalent concentric poles C' D', Fig. 2, and the other to the split solenoid-core E, which is now in its 25 lowest position, the tendency being at this time to draw the solenoid-core up toward the center of the magnet. As the movable part advances, therefore, there ultimately comes a time when the solenoid-core assumes the position shown in both figures of the drawings, 30 owing to the fact that the magnetic pull of the coil upon the armature is greater than that upon the core, the pull upon the core being practically *nil* when the median line thereof passes the median line of the magnet. Consequently the solenoid-core is advanced to the position shown and there results a counteracting force due to the action 35 of the magnet upon it, so that now the two magnetic forces are acting in opposite directions and the switch is controlled by the resultant of these two forces. When the circuit is interrupted through the conductor *w w*, the working circuit from the conductor 40 45 W will be surely interrupted as the air-gap between the armature and the magnet-poles is such that residual magnetism can produce no appreciable effect. If, however, there should still remain a small flow of current 50 through the conductor *w w*, which would under normal conditions without core E hold the armature A in its upper position, it will be apparent that owing to the counteracting force of the core in my novel switch the circuit will be surely interrupted.

This novel apparatus is especially adapted for use in connection with electric railways where it may be used to effect the connection between the current-feeder or main and sectional third rails or conductors now well known in the art and has an especial utility

in this respect in that magnetic circuit-closers as now constructed and used may retain the circuit closed from the current-feeder or main after a car has passed over the sectional conductor either by leakage or residual magnetism, while with the apparatus herein described and by the practice of the methods hereinafter claimed I am enabled to overcome these objectionable features. Although 70 my invention is especially applicable to this particular use, I desire it understood that my claims hereinafter made are to be construed of such scope as to include all uses in connection with electromagnetic circuit-closers to 75 which the same may be applied. I make no claim hereinafter to the apparatus herein disclosed, as this application is directed distinctly to a method of operation and claims to the apparatus referred to constitute the 80 subject-matter of a separate or divisional application filed by me in the United States Patent Office of even date herewith and bearing Serial No. 81,589, nor do I limit myself to the especial types of apparatus hereinbefore 85 described, and illustrated in the accompanying drawings, for practicing the method of operation attributable to such apparatus, the essence of my invention lying in the utilization of two magnetic forces acting upon 90 independent magnetic masses, both operatively attached to the movable part of an electromagnetic switch and in such manner that when a current is caused to flow through the coils of the switch-operating magnet the two 95 forces first act conjointly, tending to close the circuit, and ultimately oppose each other in such manner that the movable part of the switch is held, so to speak, in a balanced position, so that that force which tends to open 100 the switch will perform that function when the current passing through the coil is relatively small as compared to the current which the switch is designed to control.

Having thus described my invention, what 105 I claim, and desire to secure by Letters Patent of the United States, is—

The described method of operating an electromagnetic switch, consisting in controlling the movements of the movable part thereof 110 by two magnetic forces which act upon magnetically-independent magnetic masses carried by said part and in such manner that when the circuit is first closed they act conjointly and afterward oppose each other. 115

In testimony whereof I have signed my name to this specification in the presence of two subscribing witnesses.

FRANK BOURNE.
